UNITED STATES PATENT OFFICE.

MYRON H. DETRICK AND NILS RYERSON, OF CHICAGO, ILLINOIS.

ADJUSTING DEVICE.

Application filed July 18, 1923. Serial No. 652,218.

The invention relates to hardware of the kind which is usually employed in building constructions for controlling the movements of transom windows, casement windows, sliding windows, ceiling lights, doors and the like, and has for its object the provision of an improved adjusting device which is characterized in its construction, arrangement and operation by certain hereinafter described features of novelty which peculiarly adapt the device for employment in such associations. The adjusting device of the invention is also quite obviously susceptible of employment in connection with vehicles for regulating the positions of carburetor valves, heater valves, radiator shutters and the like.

The adjusting device requires the use of but one hand in effecting an adjustment of the transom window or other closure means with which the device is associated, is readily adapted to the structural peculiarities of any particular mounting surface which might ordinarily tend to conflict with the free operation of such a device, and is not subject to such localized wear as in time might act to impair the efficiency of its operation.

While the foregoing statements are indicative of the nature of the invention, other objects and advantages not herein specifically referred to will be appreciated upon a full comprehension of the novel features presented in the construction, arrangement and operation of the parts comprising the adjusting device.

In order that the invention may be readily understood, an exemplifying embodiment of the same is set forth in the accompanying drawing and in the following detailed description based thereon. Obviously the invention is susceptible of embodiment in other and varied structural forms without departure from the essence of the invention and without sacrifice of its material advantages; wherefore it is to be understood that the drawing and description are to be considered in an illustrative and not in an unnecessarily limiting sense.

50 In the drawing:—

Fig. 1 is a front elevation of a transom window which is equipped on its right-hand side with the adjusting device of the invention;

55 Fig. 2 is a view corresponding to Fig. 1, but shows a transom window which is

equipped on its left-hand side with the adjusting device;

Fig. 3 is an enlarged front elevation of the adjusting device when in its locked position;

Fig. 4 is a vertical section through certain portions of the adjusting device on the line 4—4 of Fig. 3;

Fig. 5 is a horizontal section through the adjusting device on the line 5—5 of Fig. 4.

Fig. 6 is a view which corresponds to Fig. 4, but shows the adjusting device when in its unlocked position;

Fig. 7 is a horizontal section on the line 7—7 of Fig. 6; and

Fig. 8 is a perspective view of a clutch unit which forms a part of the adjusting device.

It will be observed in the drawing that the adjusting device 10, when used for example in connection with a transom window 11, is mounted on the door-frame 12 adjacent the hinged side of the door 13 with which the transom window is associated, and operates to control the movement of the window 11 through the usual interposed mechanism 14.

The adjusting device 10 includes a mounting bracket 15, a longitudinally movable member 16 associated with the bracket, a handle 17 at the lower end of the member for transmitting to the same either a longitudinal or a rotary movement, and a clutch assemblage 18 which is contained within the mounting bracket and is adapted to lock the member against further longitudinal movement in either direction upon the member being rotated by means of the handle.

The mounting bracket 15 consists of an interiorly screw-threaded tubular portion 19 and an integral attaching base 20 at one side of and parallel to the axis of the tubular portion.

The longitudinally movable member 16 consists of a rod which is of non-circular, preferably square cross section. The member need only be of such length that a portion thereof will remain within the bracket during any extreme adjustment of the device, and is suitably swiveled at its upper end 21 to the lower end of an operating rod 22 adapted for reciprocatory movement in the mechanism 14.

The handle 17 may be of any desired type, and is advantageously one which extends radially from the lower end of the member a

distance sufficient to provide means for operating the adjusting device conveniently and without unnecessary effort.

The clutch assemblage 18 which is the feature of the adjusting device wherein the invention primarily resides, consists of a plurality of integrally associated clutch fingers 23 and an associated annular stop 24 for co-action with the clutch fingers. The clutch fingers are preferably formed in a single unit, but obviously may be formed in separate pieces. The single unit embodying the clutch fingers 23 has an axial, preferably square passage which is adapted to encompass the member in interfitting non-rotatable engagement therewith, and is characterized by a tapered nose portion 25 and an adjoining screw-threaded cylindrical portion 26 for screw-threaded engagement with the bore of the tubular portion of the bracket. The annular stop 24 consists of a sleeve which freely encompasses the member 16 and is exteriorly screw-threaded for screw-threaded engagement with the bore of the tubular portion of the bracket. One end 27 of the sleeve has an annular portion which is engageable with the nose portion of the clutch unit to cam the several clutch fingers inwardly against the member when the nose portion of the clutch unit is advanced in engagement with the annular portion of the sleeve upon rotation of the member, and the other end 28 of the sleeve has an enlarged polygonal portion for use in adjusting the position of the sleeve longitudinally within the bore of the tubular portion of the bracket. A set-screw 29 may extend through an aperture in the bracket into the bore of the tubular portion thereof and bear against the sleeve whereby to lock the same in any desired position.

The operation of the adjusting device is as follows:

When the handle is in the position shown in Fig. 6, the clutch fingers are free from frictional engagement with the member regardless of the position of the member longitudinally of the bracket, but, when the handle is turned to the right into a position substantially parallel to the plane of the base as shown in Figs. 3 and 4, the clutch fingers are turned with the member and, being in screw-threaded engagement with the bracket, are advanced against the end portion of the sleeve and cammed inwardly by the same against the member whereby to lock the member against further longitudinal movement in either direction. In order to release the member and permit further longitudinal movement of the same, it is only necessary to turn the handle in a reverse direction until the clutch fingers have been unscrewed sufficiently away from the sleeve to permit their expansion and disengagement from the member. The sleeve, be-

cause of its adjustable position with relation to the bracket, may be adjusted lengthwise of the bracket to cause the member to become locked in any desired angular position of the handle.

The most desirable location for a transom adjusting device is usually at that side of the door frame which carries the door hinges and toward which the door swings. Accordingly, when the present adjusting device is intended for use with a door which is hinged along its right-hand side, as shown in Fig. 1, it is desirable to have the handle pointing to the right when locked in a position as far removed as possible from the path of the door. In order to adapt the present adjusting device for use with a door which is hinged along its left-hand side as shown in Fig. 2, the bracket with its associated clutch need only be reversed as an entirety when being mounted on the door frame, whereupon the device will lock the member against further longitudinal movement upon being turned to the left away from the door.

We claim:

1. In a device of the character described, a mounting bracket, a longitudinally movable member associated with the bracket, an interposed plurality of clutch fingers movable against the member to lock the same against longitudinal movement upon rotation of the member relative to the bracket, an annular stop engageable with the clutch fingers to move the same against the member, and positioning means for the stop effective to vary the angular position assumed by the member when in its locked position.

2. In a device of the character described, a mounting bracket, a longitudinally movable member associated with the bracket, an interposed plurality of integrally associated clutch fingers movable against the member to lock the same against longitudinal movement upon rotation of the member relative to the bracket, an annular stop engageable with the clutch fingers to move the same against the member, and positioning means for the stop effective to vary the angular position assumed by the member when in its locked position.

3. In a device of the character described, a mounting bracket having a bore which is screw-threaded for a portion of its length, a longitudinally movable member passing through the bore, an interposed plurality of clutch fingers in screw-threaded engagement with the bore and in non-rotatable engagement with the member, and a sleeve having a portion for adjustably positioning the same in the bore and a portion engageable with the clutch fingers to cam the same inwardly against the member when the clutch fingers are advanced in engagement with the sleeve upon rotation of the member.

4. In a device of the character described, a mounting bracket having a bore which is screw-threaded for a portion of its length, a longitudinally movable member passing through the bore, an interposed plurality of integrally associated clutch fingers in screw-threaded engagement with the bore and in non-rotatable engagement with the member, and a sleeve having a portion for 55
10 adjustably positioning the same in the bore and a portion engageable with the clutch fingers to cam the same inwardly against the member when the clutch fingers are advanced in engagement with the sleeve upon 60
15 rotation of the member.
5. In a device of the character described, a mounting bracket having a bore which is screw-threaded throughout its length, a longitudinally movable member passing 65
20 through the bore, an interposed plurality of clutch fingers in screw-threaded engagement with the bore and in non-rotatable engagement with the member, and a sleeve having a portion in screw-threaded engagement with the bore and a portion engageable with the clutch fingers to cam the same inwardly against the member when the clutch fingers are advanced in engagement with the sleeve upon rotation of the member. 70
25
6. In a device of the character described, a mounting bracket which includes an inferiorly screw-threaded tubular portion and an integral attaching base at one side of and parallel to the axis of the tubular portion, a longitudinally movable member of square cross-section passing through the tubular portion of the bracket, an operating handle extending radially from the member at one end thereof, a clutch which encompasses the member in non-rotatable engagement therewith and includes a tapered nose portion and an adjoining portion for screw-threaded engagement with the tubular portion of the bracket, and a sleeve which freely encompasses the member and includes a portion for screw-threaded engagement with the tubular portion of the bracket and an annular portion engageable with the nose portion of the clutch to cam the same inwardly against the member when the nose portion of the clutch is advanced in engagement with the annular portion of the sleeve 75
30 upon rotation of the member. 80
35
7. In a device of the character described, a mounting bracket which includes an inferiorly screw-threaded tubular portion and an integral attaching base at one side of and parallel to the axis of the tubular portion, a longitudinally movable member of non-circular cross-section passing through the tubular portion of the bracket, a clutch which encompasses the member in non-rotatable engagement therewith and includes a tapered nose portion and an adjoining portion for screw-threaded engagement with the tubular portion of the bracket, and a sleeve which freely encompasses the member and includes a portion for screw-threaded engagement with the tubular portion of the bracket and an annular portion engageable with the nose portion of the clutch to cam the same inwardly against the member when the nose portion of the clutch is advanced in engagement with the annular portion of the sleeve 85
40 upon rotation of the member. 90
45
8. In a device of the character described, a mounting bracket which includes an inferiorly screw-threaded tubular portion and an integral attaching base at one side of and parallel to the axis of the tubular portion, a longitudinally movable member of non-circular cross-section passing through the tubular portion of the bracket, a clutch which encompasses the member in non-rotatable engagement therewith and includes a tapered nose portion and an adjoining portion for screw-threaded engagement with the tubular portion of the bracket, and a sleeve which freely encompasses the member and includes a portion for screw-threaded engagement with the tubular portion of the bracket and an annular portion engageable with the nose portion of the clutch to cam the same inwardly against the member when the nose portion of the clutch is advanced in engagement with the annular portion of the sleeve 95
50 upon rotation of the member. 100

In testimony whereof we have hereunto signed our names.
